UNITED STATES PATENT OFFICE.

WILLIAM D. RAY, OF LA FAYETTE, GEORGIA.

TRUSS.

Application filed May 11, 1926. Serial No. 108,324.

This invention relates to an improved appliance which is commonly known in the art as a truss, the same being designed for relief of hernia and ruptures.

At the outset, I wish to state that I am aware of the fact that a multitude of different forms of trusses have been invented and are marketed for relief of the ailments specified. It has been my experience to make an extensive investigation in this particular art and finding many defects with the already marketed devices, I have evolved and produced one which I believe to be novel and extensive improvement upon the prior devices.

Usually, the ordinary truss simply embodies a pad and supporting straps therefor, and when in place, the pad exerts a direct pressure upon the hernia, thus forcing it inwardly and allowing the surrounding portions to protrude.

It follows that I propose to provide a device of this kind which includes the pad, a highly practical one, owing to its adjustability, together with surrounding portions which extend beyond the affected spot, and constitute support, thus forming a much better and comfortable appliance if conscientiously worn, will undoubtedly benefit the patient.

The device is seen in the accompanying drawing, in which:

Figure 1 is a front elevation,

Fig. 2 is a rear elevation of the same,

Fig. 3 is a vertical section through the pad itself,

Fig. 4 is a perspective view of a portion of the pocket constituting a part of the pad, and

Fig. 5 is a detail section taken on the line 5—5 of Fig. 1.

Specifically speaking, the device is designated in its entirety by the reference character 1 and it is preferably composed of two plies of leather. The inner ply 2 is of comparatively thin and soft leather, while the outer ply 3 is of a much stiffer and stronger texture. In side elevation, the two plies of material are cut to provide radiating portions, the marginal edges of which embody the proper curvature to permit the device to accurately conform to the portions of the body with which they co-act.

At this time, I would direct attention to the fact that the marginal edge portion of the inner ply of material is folded around

the adjacent marginal edge of the complementary ply 3 as indicated in Fig. 5 and designated at 4. Then the free edge portion is brought against the ply 3 as at 5 and is permanently stitched in place. This provides a marginal binder and avoids the otherwise rough edge of the stiff ply 3, thus assuring comfort.

It will be noticed that in forming the device, a pocket 6 is provided at the center of the top portion, this pocket embodying the shape of the customary pad. The edges of the two plies are provided with openings for passage of a lace 7. Obviously, the lace is passed through the opening in the well known manner and the free ends are tied into a bow as indicated in Fig. 1. This pocket is adapted to be filled with absorbent material 8, and the feature of this construction is that the wearer can use his own discretion in making the pad either soft or hard by placing more or less material in the pocket.

Frequently, the usual pad is so stiff and hard, that the inconvenience and lack of comfort almost overbalances the relief obtained. As indicated in Fig. 1, the end portions 9 of an elastic belt are attached to the upper branches of the pliable body 1, and a felt strap or the like 10 is attached to the remaining depending branch. Obviously the belt is worn around the waist in the usual way, and the strap 10 is passed rearwardly between the legs of the wearer and is attached at its rear end to the belt.

As before stated, the gist of the invention is in the formation of the leather body which includes the three radiating branches extending from the adjustable pocket. The portions of the material projecting from the pocket serve to effectively support the part of the body around the affected part, and this overcomes undue strain and renders the device much more comfortable. It will be noticed also that due to the peculiar shape of the pliable body of leather, it may be worn either on the left side or the right side, as the wearer demands.

Having thus described my invention, what I claim as new is:—

1. As a new article of manufacture, an appliance of the class described comprising a pliable body including an adjustable pad in the form of a pocket adapted to receive a quantity of absorbent material, said body being of a configuration to form a plurality

- of radiating extensions, to the top ones of which the ends of a body encircling belt may be connected, and to the lower one of which, a leg strap may be connected.
5. 2. An appliance of the class described comprising a pliable body composed of inner and outer plies of material stitched together around their marginal edges, the central and upper portions of the plies being stitched together at predetermined points to formulate the marginal portion of a pocket, having its entrance disposed at the top edge of said body and said pocket being adapted

to be filled with absorbent material to form a pad to press directly against the affected parts, the portions of the body surrounding the pocket forming a plurality of radiating branches, the two top ones of which are in alinement with each other and are adapted for connection of the ends of a body encircling strap, and the remaining one of which depends from the bottom portion of the pocket and is adapted for connection of a leg strap.

In testimony whereof I affix my signature.

WILLIAM D. RAY.
